PLACER MACHINE

Leslie A. Lamberson, Lander, Wyo., assignor of
one-half to Eva G. Lamberson, Lander, Wyo.,
and one-half to R. F. Granger, Denver, Colo.

Application February 14, 1935, Serial No. 6,567

1 Claim. (Cl. 209—44)

This invention relates to a placer machine or ore concentrator and an object of the invention is to provide a device of this character which may be easily transported from place to place and which will be found especially adapted for use in placer mining.

The invention, together with its objects and advantages will be best understood from a study of the following description, taken in connection with the accompanying drawings, wherein:

Figure 1 is a top plan view thereof.

Figure 2 is an elevational view of one side of the machine.

Figure 3 is an elevational view of an opposite side of the machine.

Figure 4 is a longitudinal sectional view through the concentrator trough or drum.

Figure 5 is a top plan view thereof.

Figure 6 is a top plan view of the grizzly screen or riffle rack.

Figure 7 is a longitudinal sectional view therethrough.

Figure 8 is a transverse sectional view through said grizzly screen or rack.

Referring to the drawings by reference numerals, it will be seen that 10 indicates generally a frame or chassis supported at the front and rear thereof by suitable wheels 11.

Rising from the frame 10 is a skeleton frame structure 12 which at the front and rear ends thereof is provided with supports 13 and 14 supporting clamps 15 and 16, the clamp 16 being disposed in a higher plane than the clamp 15. A rod 17 is supported at an incline and has the ends thereof secured by the clamps 15 and 16. From the rod 17 there is suspended for rocking movement relative thereto the concentrator trough or drum 18 into which the dirt, gravel and clay carrying the ore are introduced through 40 a hopper 19 suitably mounted on one end of the drum.

For causing the drum 18 to rock laterally back and forth, there is secured to the open top side of the drum a transverse bar 20 which, at one end, is connected through the medium of a connecting rod 21 with an arm 22a on one end of a suitably mounted shaft 22 that is driven from a second shaft 23 through the medium of belt and pulley means 24.

As the gravel, clay, and dirt pass through the drum 18, they are thoroughly washed by water supplied to the drum from a suitable source of supply through the medium of piping 25 and pump 26.

55 The material is discharged from the lower end

of the drum 18 onto a chute 24, and by this chute delivered to the riffle rack or grizzly screen indicated generally by the reference numeral 28.

The screen 28 is suspended by suitable suspension means 29 and this screen includes, as clearly shown in Figures 6 to 8 inclusive, a trough section 30 having a bottom 31 provided for the greater portion of the length thereof with a depression 31a, and at the end thereof remote from the depression 31a there arises from the bottom 31 an end flange or wall 32.

The raised portion of the bottom 31 is provided with corrugations 33, and arranged in the recessed or lowered portion 31a of the bottom is a screen or riffle 34 that is secured in position 15 through the medium of cleats 35 and pivoted thumb members 36 that engage the sides or flanges of the riffle 34. The riffle elements per se of the riffle assembly 34 are disposed at a suitable angle to the bottom of the riffle assembly and 20 are so inclined and spaced as to force the gold particles towards the center. In this connection, it will be noted that beneath riffle 34 there is a mat of suitable rubber or rubber composition so as to provide a suitable surface for the precious 25 metals which accumulate in the spaces between the riffles.

The tailings discharging from the vibrating or reciprocating riffle assembly 28 are received on a power driven elevator 37 of suitable form and construction that extends upwardly and outwardly as shown. The elevator is driven from a suitably mounted shaft 38 through gearing 39 and this shaft 38 is driven through the medium of belt and pulley means 40 from a shaft 41. The shaft 41 is in turn driven through the medium of belt and pulley means 42 from the shaft 23 that in turn is driven by belt and pulley means 23a from a suitable motor or prime mover 43. The aforementioned pump 26 is driven from the shaft 23 40 through the medium of belt and pulley means 45.

For reciprocating the grizzly screen or riffle assembly 28 there is suitably provided on the shaft 23 a cam or eccentric member 46 about which is disposed an eccentric band 47 having extending 45 therefrom an angular arm 48 secured to a rod 49 that is pivoted at one end as at 50 to a lug on the bottom of the trough member 30 of said riffle or grizzly screen.

For taking care of the large rock that may 50 spill out of the drum 18 the chute 27 has a branch 27a thereof leading therefrom to an inclined trough 51 mounted at one side of the aforementioned skeleton frame structure.

The waste water collects in a transverse trough 55

52 and from this trough enters into a tank 53 that may be placed at one side of the device and from which the water may be drawn through piping 54 by the pump 26 to be used over and over again.

Referring again to the drum 18, it will be seen that the same has the trough 19 thereof formed integral therewith and extending across the top of the trough are straps 55 provided on their under sides with bearings 56 for accommodating the rod 17 whereby provision is made for rockably suspending the drum from said rod.

Arranged within the drum is a false bottom structure 57 that is suitably secured in the drum and spaced from the bottom and side walls of the drum. At one end the false bottom is provided with perforations 58 through which the gold, when washed loose from the gravel and the like, passes into the space between the bottom of the drum and said false bottom. From this space, the fine particles of precious metal pass through

the perforations 58 onto the aforementioned chute 27 to be guided thereby onto the riffle or grizzly screen assembly.

To thoroughly agitate and grind the clay and other sticky substance thereby serving to the better separate the precious metal from the foreign substance, the false bottom 57 is provided with a plurality of haphazardly arranged projections 60.

What is claimed is:

In a placer machine, an oscillating trough provided adjacent one end thereof with a series of perforations, and a false bottom arranged in the trough and spaced from the bottom of the trough, said false bottom being provided adjacent one end with perforations, said false bottom between said perforations and the ends thereof remote from the perforations being also provided with a series of projections for subjecting the contents of the trough to a grinding action.

LESLIE A. LAMBERSON.
